The ornamental design for a helmet, as shown and described.

DESCRIPTION

FIG. 1 is a top front left isometric view of a helmet, showing my new design;

FIG. 2 is a top rear right isometric view thereof;

FIG. 3 is a front view thereof;

FIG. 4 is a rear view thereof;

FIG. 5 is a right view thereof;

FIG. 6 a left view thereof;

FIG. 7 is a top view thereof; and,

FIG. 8 is a bottom view thereof.

The broken lines in the figures depict portions of the helmet that form no part of the claimed design.

1 Claim, 8 Drawing Sheets(56)
